Specification for Design.

Patented May 22, 1917.

Application filed March 10, 1917. Serial No. 154,045. Term of patent 7 years.

To all whom it may concern:

Be it known that we, MARTIN L. BOWDEN and MARTIN L. BOWDEN, Jr., citizens of the United States, and residents of Brooklyn, in the county of Kings and State of New York, have invented a new, original, and ornamental Design for a Ring or Similar Article, of which the following is a specification, reference being had to the accompanying drawing, forming part thereof.

Figure 1 herein is a perspective view of our improved ring.

Fig. 2 is a fragmentary cross section of the ring shown in Fig. 1 when the latter is upright.

We claim:—

The ornamental design for a ring or similar article as shown.

Signed at New York, in the county and State of New York, this 26th day of February, 1917.

MARTIN L. BOWDEN.
